UNITED STATES PATENT OFFICE.

GEORGE PATTEN, OF WASHINGTON, DISTRICT OF COLUMBIA.

METALLIC ROOFING-PLATE.

SPECIFICATION forming part of Letters Patent No. 296,610, dated April 8, 1884.

Application filed December 28, 1883. (No model.)

To all whom it may concern:

Be it known that I, GEORGE PATTEN, a citizen of the United States, residing at Washington, in the District of Columbia, have invented 5 a new and useful Improvement in Metallic Roofing-Plates, of which the following is a specification.

My invention refers to the construction of metallic plates for roofing, whereby separate 10 plates of any suitable dimensions are united in overlapping tiers by certain lateral and transverse connections, hereinafter to be described, which, while admitting of the expansion and contraction due to the material, securely attach 15 the plates to each other and to the roof-sheathing in a manner which effectually prevents leakage and favors ventilation.

In the accompanying drawings, which form part of this specification, Figure 1 is a plan 20 view, showing two plates of the lower tier and one of the second tier. Fig. 2 is a vertical section on line $x-x$ of Fig. 1. Fig. 3 is a vertical section on line $y-y$ of Fig. 1. Fig. 4 is a transverse section of the two lower plates, showing 25 longitudinal joint and position of upper plate. Fig. 5 is an edge view of plate, showing position of pendent flanges. Fig. 6 is a transverse section on line $v-v$, showing upturned flanges. Fig. 7 is a transverse section of plates in adjacent tiers, showing chamber between on enlarged scale. Fig. 8 is a side view of fastener on enlarged scale. Fig. 9 is a top view of same. Fig. 10 is a face view of same.

The same letters of reference denote the same 35 part in all the figures.

Each plate $P P'$ has upon one side a single corrugation, e , and an upturned flange, f , inclining in opposite directions and separated by a valley, n . Upon the other side are two 40 corrugations, a and b , similarly inclined, with a valley, c , between them, so that the double corrugation of one plate will fit upon the single corrugation and flange of the adjacent plate and form a water-tight joint, the opposite inclination of the corrugation and flange f serving 45 to confine the double corrugation of the other plate thereto.

In the lower portion of the plate P' is the upward-projecting hood R , extending the 50 overlapping distance of the tiers, designed to embrace and cover the upper portion of the

lateral joint, being secured thereon and thereto by the fastener B , which serves to attach the lower plates to the sheathing, close the joint-valley, and hold the upper plate, P' , up- 55 on the plates P beneath.

On each side of the hood R the lower edge of the plate is formed with pendent triangular flanges m , deepest at the recess or hood, and terminating at the lateral corrugations e and b , as shown in Fig. 5. The upper edge of the plate has similar triangular flanges, extending upward, highest at the corrugation, and terminating near the middle of the plate, as seen at $r-r'$, Fig. 6.

Above the hood R is an upward-projecting chamber, C , of circular or other suitable form, and of such dimensions as to occupy the middle of the plate, serving to stiffen the plate, in addition to constituting an air-chamber. 65

To cover a roof with these plates, the first plate of the lower tier at the right is attached by bending down the double corrugation and nailing to the edge of the roof-sheathing, and secured at the left by nails through the perforations v in the valley n . The double corrugations $a b$ of the adjacent plate are then passed over the corrugation e and flange f of the first plate, forming the joint between the plates, the second plate, P , being secured by 70 nailing through the openings v in the valley n , and so throughout the entire lower tier of plates. The securers B are then placed in each valley by nailing through the openings o of the arms d and perforations i in the plate- 75 valleys. The bar d presses upon the double thickness of plate in the valley, the plate p closing the valley, and the arm s projecting in direction of the top of the plate. The hood R of a plate, P' , of the second tier covers the 80 portion of the joint of the plates P below as far as the trapezoidal plate p , whose top is beneath the lower edge of said hood when in position under the arm s , as shown in Fig. 2. The hood R is of such depth that when drawn 85 down by the securer B the lower edges of the flanges m will reach the surface of the plates beneath, the effect of the securer B being to hold the superposed plate firmly upon those below, while the plate p blocks the valley of 90 the joint. In giving the upper plate this position its double corrugation engages the cor-

rugation and flange of the adjacent plate on the right, securing that side in position, the other side of the plate P' being attached to the sheathing by nailing through the perforations v , as described for the lower tier. The pendent flanges m are thus drawn closely upon the plates below, as shown in Fig. 4, forming a square lower edge to the upper plate, P' . The upturned flanges $r r'$ at the top of the lower plate press against the lower surface of the plate P' and interpose a barrier to the upward passage of water, the two sets of flanges and the surfaces of the plates adjacent to them forming the wedge-shaped anti-capillary ventilating-chambers shown in Fig. 7. Moreover, the slight inclination thus given the plate P' adjacent to the hood R serves to throw the water over to the sides of the plate, where leakage cannot occur. The spring caused by the side fastening of the plate and the triangular flanges at its ends adds materially to the stiffness of the attachment to the roof.

By the construction hereinbefore described the plates are firmly secured to the sheathing and to each other in a manner which readily admits of contraction and expansion, while both transverse and lateral joints are formed, so as to be non-leaking. Instead of forming the single corrugation and flange on the left side of the plate, they may be placed on the opposite side, in which case the laying of the plates will begin at the lower left-hand corner of the roof. Moreover, the flange and all the corrugations may be formed perpendicular to the face of the plate, and after the corrugations of the second plate embrace the cor-

rugation and flange of the first the opposite inclination may be given to both sets at the same time by a suitable tool, thus forming the joint, as above set forth.

Having described my invention and the operation thereof, what I claim as new and of my own invention, and desire to secure by Letters Patent, is—

1. The construction of a metallic roofing-plate with an oppositely-inclined double corrugation on one side and a similarly-inclined corrugation and flange on the other side, with valleys between them, substantially as set forth, for forming the lateral joints between adjacent plates.

2. The hood R , in combination with the securer B , substantially as described, whereby the upper tier of plates is firmly attached to those beneath and the joint-valleys closed.

3. In combination with the hood R and the securer B , the pendent triangular flanges m , for forming the transverse joint, substantially as described.

4. The combination of the upturned triangular flanges $r r'$, pendent triangular flanges m , and securer B with the lateral joints, substantially as and for the purposes set forth.

5. The combination of the chamber C and hood R with the two sets of triangular flanges and the plate-surfaces, substantially as and for the purposes set forth.

GEORGE PATTEN.
